[57] CLAIM

The ornamental design for a combined packaging container and target for an air gun, substantially as shown and described.

DESCRIPTION

FIG. 1 is a perspective view of a combined packaging container and target for an air gun showing my new design;

FIG. 2 is a front elevational view thereof;

FIG. 3 is a bottom plan view thereof;

FIG. 4 is a top plan view thereof;

FIG. 5 is a rear elevational view thereof; and

FIG. 6 is a side elevational view thereof, the opposite side being a mirror image thereof.
